UNITED STATES PATENT OFFICE.

LOUIS G. MORTEN, OF JERSEY CITY, NEW JERSEY.

TENNIS RACKET.

Application filed March 6, 1924. Serial No. 697,243.

The present invention relates to improvements in tennis rackets and more particularly refers to the adjustment of the strings in the racket frame.

5 It is an object of the invention to provide for the tightening of the strings in the racket frame from time to time as they become loosened and to accomplish this by a structure which will admit of the individual 10 binding of the strings without involving too great an expense in the production of the racket and without involving undue labor or trouble in effecting the adjustment.

Another object of the invention is to effect 15 the stringing of the racket and the adjustment of the strings without requiring any pinching of the strings. This pinching of gut strings, or in fact metallic strings or wires, tends to cause the early destruction 20 of the string and it also avoids that degree of tautness of the string which may be secured by placing the string under axial tension throughout its entire length.

With the present invention, the strings 25 may be loosened when the racket is not in use, thus relieving the strings from tension and enabling them to be tightened whenever the racket is about to be used. The loosening of the strings when the racket is not in 30 use will prolong the life of the strings.

A further object gained by the present device is that the individual owner may string his own racket when and as he desires, and dispenses with the necessity of 35 sending the racket to a manufacturer or person making a business of it. This not only saves time, but expense in stringing rackets.

With the foregoing and other objects in view, the invention will be more fully described hereinafter, and will be more particularly pointed out in the claim appended hereto.

In the drawings, wherein like symbols 45 refer to like or corresponding parts throughout the several views,

Figure 1 is a fragmentary front view, with parts in section, of a tennis racket constructed in accordance with the present invention.

49 Figure 2 is an edge view of the same.

Figure 3 is a section on line 3—3 in Figure 1.

Figure 4 is an enlarged fragmentary view taken through the screw plug and adjacent portions of the racket.

55 Figure 5 is a section taken on the line 5—5 in Figure 4.

Figure 6 is an exterior end view of a portion of the racket and plug, and

Figure 7 is an interior fragmentary view 60 of the same parts.

Referring more particularly to the drawings 7 designates a portion of the handle of a tennis racket and 8 the substantially oval frame thereof which is usually made of 65 wood, although it may be of metal or other appropriate material. The frame 8 is strung with longitudinal and transverse strings or wires 9 and 10 respectively and these strings are usually of gut, although they are sometimes of metallic wires. For purposes of illustration I have shown merely three of the transverse strings or wires 10 as being mounted in the frame 8, but it is understood 70 that each transverse and longitudinal string 75 or wire may be connected in the same manner, so that individual adjustment may be secured.

The frame 8 is shown as provided along its outer edge with perforations 11 to receive 80 the strings, the strings being knotted as shown at 12 to avoid pulling through the perforations.

The strings or wires 10 pass through the 85 perforations 11 and extend across the open interior portion of the frame 8 to the opposite side thereof. At the opposite sides the strings are received through the openings 14 made in the plugs 15. These plugs are of appropriate length and diameter and 90 they are shown as screw threaded upon their outer surfaces as indicated at 16 in order to take into similar threads 17 formed within the cylindrical passages of the frame 8. These cylindrical passages are open both on 95 the exterior and interior sides of the frame 8, and the bore of each passage extends in axial alignment with the opening 11 at the opposite side of the frame, so that a string extends directly or diametrically from one 100

side of the racket frame to the other and directly in alinement through the opening 11 and the opening 14 of the respective plug 15. A washer 18 is shown as provided upon the outer end of each plug, but need not be of as great diameter as the plug. This washer is also perforated to receive the string and the string is knotted as indicated at 19 to prevent its being pulled through the washer and plug.

In Figure 6 the inner end of the plug is shown as provided with cross slots 20 and 21 to opposite sides of the cylindrical opening, the slots being in the same diametric line and being adapted to receive the forked end of a screw driver or other tool as indicated in dotted lines at 22 in Figure 4.

In the use of the device the string is first knotted at one end as indicated at 12, the other end being threaded through the opening 11, after which the string may be pulled through the opening 11 until the knot 12 is drawn against the side of the frame.

The opposite end of the string may then be threaded through the opening 14 in the plug, and this will preferably be done before the plug is inserted in the racket frame. The washer 18 is also threaded or slipped on after the plug, and both washer and plug may be moved along the string to give ample opportunity to form the knot 19. The plug 15 may then be inserted with the washer and foremost from the inside of the frame 8 into the threaded opening 17 and by the use of the tool 22 or other suitable implement the plug is rotated to cause it to travel axially outward thereby gradually placing the string 10 under tension. The rotation is continued until the string is drawn taut to the desired degree and as many as desired of the other strings of the racket may be treated in like manner. When undue slackness is developed in the strings the various plugs 15 may be turned to take up this slack.

It will be noted that the strings lie through the openings 11 and through the plugs 15 in the same direct line in which they cross the racket frame, and consequently the line of tension is all in one continuous and uninterrupted straight path. There is no application of pressure at an angle such as would tend to cut the gut or wire and incidentally diminish the pressure or require greater effort than in the present case to secure the same tautness.

The washer 8 may slip around to prevent rotation of the strings as it is not desirable to twist the strings, they being given an appropriate amount of twist in the course of their manufacture. All friction or tendency to cut the string at or near the knot 19 is removed by having the stationary washer 18 take the pressure off the knot 19. The forked tool 22 straddles the string. Of

course other type of tool may be used and the slots 20 and 21 may be placed upon the outside end of the plug 15 if desired in which case the forked end of the tool is desirable to bridge the washer 18.

The plugs may be used at both ends of the strings if desired or only at one end of the strings as shown. The construction is inexpensive to manufacture, easy to adjust and in its use the life of the strings will be prolonged, and the resiliency will be increased due to the fact that there is no pinching of the strings, but that there is always a constant force holding the strings under longitudinal tension, this tension being increased whenever desired by simply turning the plugs.

Of course the washer 18 is optional and may be used or discarded, but its employment relieves the string of cutting at least to some extent.

The handle 7 of the racket is shown in Figures 1 and 2 as being of hollow metal. The metal affords the necessary rigidity and strength and the fact that the handle is hollow saves considerable material and undue weight of the racket and aids in a delicate balance.

The oval frame 8 may also be made, at least to same extent, of a hollow construction in order to aid in the matter of lightness and balance. Of course the portions where the plug enters are necessarily solid or provided with interior walls to take the threads which engage the plugs, however, the oval frame may be made solid if desired. Where the oval frame 8 is hollowed out it will be somewhat similar to channel iron, as shown in Figures 1 and 2.

Of course it will not be necessary to use plugs on each string. Some plain strings may be used attached in the ordinary way and the plugs might alternate for instance first on one side and then on the other and this alternate use is the preferred construction. Of course plugs might be used at both ends of each string.

It is obvious that various changes and modifications may be made in the details of construction and design of the above specifically described embodiment of this invention without departing from the spirit thereof.

What is claimed is:—

A tennis racket comprising a frame having at one side an opening just wide enough to receive a string and provided with a recess at the outer end of the opening, a string knotted at one end, the string adapted to pass through the opening and the knot to lie in said recess, said frame having at its diametrically opposite portion an opening of greater diameter, a plug secured in this opening, said threaded opening being open at

both ends and said plug having a passage axially therethrough of a diameter to snugly receive the string and being substantially in alignment with the opening at the opposite side of the frame, the opposite end of the string being passed through the passage in said plug, said plug having divided diametric slots on one end to receive a tool

whereby to rotate the plug, and a washer upon the outside of the plug adapted to receive the other knotted end of the string to avoid cutting of the string by the rotating plug.

In testimony whereof I affix my signature.

LOUIS G. MORTEN.
